UNITED STATES PATENT OFFICE.

GUY E. DITZLER, OF HINSDALE, ILLINOIS, ASSIGNOR OF ONE-THIRD TO JOSEPH T. COCHRAN AND ONE-THIRD TO RALPH M. KRIESER, BOTH OF CHICAGO, ILLINOIS.

SURPRISE DEVICE.

Application filed December 27, 1926. Serial No. 157,137.

These improvements relate to small devices which will ordinarily be made of cardboard material and in a form suitable for mailing, and which, on being removed from the envelope, will develop action producing surprise to the person receiving it through the unexpectedness of such or any action.

In some aspects of the invention it relates to toys; but it has been designed chiefly as a medium for advertising, and relates also to that art.

Its object as a toy is to provide amusement, while from the standpoint of an advertising device its chief object is to provide a cheap, simple, light-weight device which may have substantially large surfaces for advertising purposes and which will accentuate the impression of the advertising through the surprise feature of the device, and also maintain the advertising matter long before the recipient through the toy features by creating continued interest and inducing a preservation of the article.

In the drawings Figure 1 is a perspective of the device in folded condition and as held within an ordinary envelope which is shown by dotted lines; Fig. 2 is an edge view showing relative positions of parts automatically assumed when the device is normally withdrawn from the envelope; Fig. 3 is a fragmentary end view showing details at the lower right-hand corner of Fig. 2; Fig. 4 is a fragmentary top plan with the swinging member laid down flat against the base; and Fig. 5 is a sectional view on the line 5-5 of Fig. 4.

The construction illustrated comprises a base 10 which in my practice consists of a piece of cardboard material rectangular in shape and of such dimensions as to be accommodated within an ordinary business envelope in the neighborhood of four and one-fourth inches wide and nine and one-half inches long. The dimensions of the base may vary within wide limits.

Mounted on the base for swinging movements is a swinging member 11, which may consist of one part or of several parts. In the drawings there are two such parts shown as 11^a and 11^b, and these parts may be considered to be also of cardboard material. When of several parts they are hinged together as at 12.

The lower part marked 11^b is hinged to the base at 13 and the length of the respec-

tive parts and their arrangement are such that the part as 11^a next to the part 11^b may fold upon the part 11^b through the hinge at 12, and the two parts may then be folded as a unit upon the hinge 13 so as to lie flat upon the base as shown in Fig. 1.

The swinging member 11 is preferably somewhat narrower than the base so that when the envelope is cut along a side edge and the device within is grasped between a finger and thumb the swinging member will escape being held and will remain free for action.

The hinge construction at 12 is developed in my practice by forming the parts 11^a and 11^b as one piece and then scoring it at the line 12 of Fig. 4 so that it will bend readily. The lower hinge, at 13, is formed by scoring the same piece on the line 13 of Fig. 4.

The swinging member is permanently held upon the base by securing the short extension 11^c thereof to the base as by glue. The part 11^c is first formed, however, with a stop member 14, which is a tab cut free from the rest of the material on the lines 15 and 16 of Fig. 4, while on the line 17 the tab 14 remains attached to the part 11^c, the line 17 indicating scoring whereby the tab 14 may swing on this scored line as upon a hinge. This tab 14 constitutes a stop for the swinging part 11^b, as shown in Fig. 2, and, in order that the swinging member may preferably lean back somewhat beyond the vertical, for better viewing effects, as shown in Fig. 2, the line at 16, Fig. 4, is at an angle to the line 17 other than a right angle, namely, an acute angle.

When the device is received through the mail it is in folded condition, as shown by Fig. 1. When it is withdrawn from the confinement of the envelope the swinging member parts automatically assume their relative positions shown in Fig. 2. For the purpose of this automatic movement I employ spring means associated with the several parts to cause simultaneously an unfoldment of the parts and a swinging upward of the member 11 as a whole.

Considering first the spring or tension means for raising the part 11^b, I provide, first, as holding means, and as a simple and cheap expedient, a small ear or lug 20 in the part 11^b at a substantial distance from the hinge 13 and a similar ear or lug 21 in the base 10, and I then hook over these

anchoring projections an ordinary rubber band 22 in endless or ring form, the rubber band being under tension when so positioned. The rubber band passes around the end of the section 11^a spaced from the hinge 13, and a pull upon the part 11^b is thereby developed tending to draw it upward into its final position shown by Fig. 2.

When the member 11^b is depressed so as to lie substantially parallel with the base the stop 14 may also be pressed down substantially flat as in Fig. 1, in which position, as shown by Fig. 4, the rubber band 22 is under the tab. When the parts are released for action the parts of the rubber band adjacent to the tab rise more and more away from the base and the tab is swung outward and automatically put in position to act as a stop, as shown in Fig. 2, limiting the movement of the part 11^b under the spring action of the rubber band.

Turning now to the spring means between the parts 11^a and 11^b I form tabs or catches 24 and 25 on these parts respectively and hook over them a taut rubber band 26. In order that a leverage action may be developed to swing the part 11^a I provide, as a preferred construction, a small piece of firm and strong cardboard material 27 secured to the part 11^a as by glue or by means of a staple 28. This piece 27 extends at 27^a beyond the line 12 to constitute a lever, and also a stop.

Fig. 1 shows how the rubber band 26 passes around this lever extension 27^a when the part 11^a is folded under the part 11^b. In that position the tendency of the spring band 26 is to swing the part 11^a on the hinge line 12. When the device is taken out of the envelope and the parts are thus freed for action, such movement automatically occurs, and, when the part 11^a is in the plane of the part 11^b, as shown by Fig. 2, this extension 27^a constitutes a stop limiting the further swinging movement of the part 11^a on the part 11^b.

The base 10 has a substantially large area which may contain considerable advertising matter. The swinging member 11 may also contain advertising matter, or it may serve as a carrier and support for some other object, for example a figure cut out from other material and secured upon these members 11^a and 11^b. Thus in Fig. 3 the dotted lines 27 may be taken to indicate a portion of a cut-out representing a woman, and which figure would suddenly and unexpectedly rise from a flat card held in the hand and smile into the face of the recipient of the device.

The structure illustrated is not only highly surprising to the original recipient, and in a very pleasant and agreeable way, but its amusement features are such as to cause it to be used as a surprise device for the recipient's friends who are in turn given the en-

velope for a like experience. The device is thus handled a great deal, played with, and preserved—all to the effect that its advantages as an advertising medium are greatly enhanced.

Important features of the device are its simplicity and very low cost.

I contemplate as being included herein all such changes, variations and departures from what is thus specifically illustrated and described as fall within the scope of the appended claims.

I claim:

1. In a surprise device of the character described, the combination of a flat and elongated base member of sheet material, an elongated swinging member of sheet material mounted at one of its ends on the base member to lie substantially upon and parallel with the base member and to swing upward and assume a normally upright position thereon, said swinging member being narrower than the base member, with a stop carried by one of said members and arranged to contact the other thereof when the swinging member has assumed a normally upright portion on the base approximately ninety degrees from the base, and a tension spring connected to each of said members and arranged to draw the swinging member upward by a direct pull upon it when released from its position substantially parallel with the base.

2. In a surprise device of the character described, the combination of a base, an elongated swinging member comprising a plurality of parts jointed together so as to fold one upon another and in such folded condition to lie substantially upon the base, the swinging member being mounted at one of its ends hingedly upon the base to swing normally upward thereon, spring means associated with the several parts and with the base respectively for automatically causing the several parts to unfold and the member as a whole to swing upward from the base when released from such folded condition and with the parts lying substantially upon the base, together with stop means associated with the respective parts for limiting their unfolding and upwardly swinging movements.

3. In a surprise device of the character described, the combination of an elongated member of cardboard material or the like, an elongated swinging member of sheet material and comprising a plurality of parts jointed together so as to fold one upon another and in such folded condition to lie upon and substantially parallel with the base, the swinging member being mounted at one of its ends hingedly upon the base to swing normally upward thereon, rubber band tensioning means associated with the several parts and with the base respectively

arranged to pull directly upon them for automatically causing the several parts to unfold and the member as a whole to swing upward from the base when released from the folded condition and from said position of the parts substantially parallel with the base, together with stop means for limiting the unfolding and the upward swinging movements respectively when the swinging member has moved through approximately ninety degrees.

4. In a surprise device of the character described, the combination of a base of sheet material adapted to be encompassed by an envelope, an elongated swinging member of sheet material narrower than the base and mounted at one of its ends upon the base to lie substantially parallel therewith and to swing normally upward therefrom, said swinging member comprising a plurality of sections hingedly connected together end to end and adapted to fold one upon another, and rubber band spring means associated with the several sections and with the base respectively for automatically causing the sections to unfold and the swinging member as a whole to swing upward from the base when released from folded condition and from the position in which the parts lie substantially parallel with the base, with stop means adjacent to each hinge connection for limiting the unfolding and upwardly swinging movements respectively.

5. In a surprise device of the character described, the combination of a base, an elongated swinging member mounted at one of its ends hingedly upon the base to lie substantially parallel therewith and to swing normally upward thereon, a rubber tension-

ing spring held upon the base and upon said swinging member and arranged to draw the swinging member upward by a direct pull upon it when released from its position substantially parallel with the base, and a stop in the path of swinging movement of the swinging member for limiting its upward movement to substantially ninety degrees from the base.

6. In a device of the character described having a base and a swinging member hinged upon the base, the combination therewith of an elastic tension member secured to the base and to the swinging member at places respectively spaced from the hinge connection between them and arranged to draw the swinging member away from the base by a direct pull upon it, and a stop movable into the path of swinging movement by the movement of the elastic member for limiting the movement of the swinging member under the drawing strains of the elastic member to substantially ninety degrees.

7. In a device of the character described comprising a base and a swinging member having two parts mounted on the base for swinging movements, the combination therewith of means for automatically providing a swinging movement of one of said parts relative to the other thereof comprising a hinge-like connection between the two parts, one of said parts having an extension beyond the hinge-like connection, and taut elastic means secured to the one of said parts having the extension and passing over said extension.

GUY E. DITZLER.
